HAND WHEEL FOR A VALVE

Donovan B. Wallace and Gary D. Counselor, Muskegon,
Mich., assignors to Westran Corporation

Filed Oct. 28, 1975, Ser. No. 626,258

Term of patent 14 years

Int. Cl. D23—01

U.S. Cl. D23—30

FIG. 1 is a perspective view of a hand wheel for a valve embodying our design;

FIG. 2 is a top plan view thereof;

FIG. 3 is a side elevational view thereof;

FIG. 4 is a bottom plan view thereof; and

FIG. 5 is a side elevational view taken ninety degrees from that shown in FIG. 3.

We claim:

The ornamental design for a hand wheel for a valve, as shown.
